UNITED STATES PATENT OFFICE.

CHARLES C. MILLER, OF FORT WAYNE, INDIANA.

BAG.

1,102,426.

Specification of Letters Patent.

Patented July 7, 1914.

Application filed July 12, 1912. Serial No. 708,946.

To all whom it may concern:

Be it known that I, CHARLES C. MILLER, a citizen of the United States, and resident of Fort Wayne, in the county of Allen and 5 State of Indiana, have invented new and useful Improvements in Bags, of which the following is a specification.

My present invention relates to bags and particularly to bags for the storage of articles to protect the same from dust, moth, vermin and the like. Its object is to provide a bag which shall be cheap, simple and efficient for the purpose of protecting garments and the like from dust, insects and the 15 like, and which shall be readily opened for the insertion and removal of the garments.

In most bags heretofore in use for the purpose of protecting garments the mouth of the bag is at the top and the user has 20 considerable difficulty in inserting garments, particularly those which are of some considerable length, such as overcoats, gowns and the like, and the user cannot be certain that the garments are hanging freely so as 25 not to be crushed when the bag is closed.

The particular object of my invention is to provide a bag which can be opened to greater extent than any heretofore in use so that the user may easily insert the garment 30 and be assured that it will not be crushed when the bag is closed.

Other objects will be set forth hereafter.

In the accompanying drawings I illustrate the preferred form of my invention in 35 which—

Figure 1 is a front elevational view of a bag (closed) constructed according to my invention; Fig. 2 is a fragmentary front elevational view of the same with the mouth 40 and front open; Fig. 3 is a sectional view on line 3—3; Fig. 4 is a sectional view on line 4—4 and Fig. 5 is a sectional view of the front side of the bag on line 5—5.

Referring to the drawings the bag consists 45 of a front 10, back 11 and two extensible sides 12 which are preferably formed out of one sheet of material such as suitable paper. The bottom of the bag is permanently closed in any suitable and usual manner.

On the exterior of the back is a suitable 50 hanger 13 and on the interior of the back are suitable garment hooks 14 which are secured to the back by rivets 15 which pass through the hanger, the back and the hook 55 supporting plate 16. Adjacent the outer upper edge of back 11 is secured an exten-

sion or flap 17 (Fig. 4), the upper portion of which is folded over a reinforcing strip 18 of suitable material which is preferably heavier than the material forming the flap. 60 Between the extension and back I provide a reinforcing strip 19 which is preferably fabric, the fabric extending upwardly between the folds of the flap as plainly seen in Fig. 4. Lateral ears 20 project from strip 65 19 which are secured to the folded sides 12 adjacent the top edge of the same in order to reinforce the upper corners between the back and sides. At opposite ends of flap 17 and to the front side thereof, are secured two 70 clamps 21 which serve to secure the parts in the closed position as hereafter explained.

Instead of attaching a strip to back 10 to form flap 17 I may cut the sheet so that the upper portion of the back will project above 75 the front similarly to flap 17 as seen in Fig. 3.

The front of the bag is formed by overlapping the ends or sections 22, 23 of the sheet, the lower portions, as between lines 80 24, 25, being secured together. Section 23 is slit transversely substantially midway its length as is indicated by line 26 to form a flap 27 and the section is creased from approximately the inner end of the slit to the 85 upper corner as is indicated by dotted line 28. The side edge of the flap is reinforced by a suitable strip 29 which overlaps the edge and is secured thereto, and a similar reinforcement 30 is similarly secured to the 90 top edge of the flap and the folded side 12. One member 31 of a socket clasp is secured to the flap 27 adjacent the side edge and is adapted to coact with the other member 32 of the clasp which is secured adjacent the 95 edge of flap 33 which is provided on section 22. The clasp serves as a guide to insure the register of the two edges of the flaps in the closing operation of the same as 100 hereinafter described and also secures the edge portions of the flaps together.

A strip 34 is secured to the side edge of section 22 to increase the width of flap 33 in order that the flap may be folded with flap 27 as hereinafter explained. The side 105 edge of the flap is reinforced by a strip 35 similar to reinforcement 29 on flap 27 and the top edge of the same is similarly reinforced by strip 36 which is also extended along the top edge of the adjacent folded 110 side 12.

In the crotch between the two flaps is a re-

inforcement 37 of suitable material which is extended under the lower edge of each flap and upwardly on the outer surface of the same. Another reinforcing strip 38 is secured to the outer surface of section 23 adjacent to the base of the crotch, or said strip 38 may be a part of reinforcement 37.

Section 22 is creased approximately on line 39 similarly to section 23.

10 Suitable clasps 40 are secured to the front side of flap 33 adjacent reinforcement 35 and are adapted to secure the two flaps in folded relation as is about to be described.

With the bag open, sides 12 extended, and 15 the flaps 27, 33 turned back at the creases onto front 10, there is presented a very large opening through which the garment may readily be passed in order to insert the same into the bag. To close the bag the flaps are 20 brought together with the inner portions of reinforcements 29 and 35 in contact. Socket 32 is engaged on stud 31 and the two reinforced edges are folded over along the inner edge of reinforcement 29 onto flap 27. This 25 fold brings clasps 40 to the front of the fold. A second fold of the two flaps is then made on approximately dotted lines 41. The latter fold carries the clasps between the two folds and flap 27, the tongues of the clasps 30 projecting outwardly from the folds. The tongues of the clasps are then brought over onto the front side of the folds or the front side of flap 33 in which position the clasps securely retain the folds of the two flaps. 35 Extension 17 or the upper end of back 11 is then folded forwardly onto front 10 as previously closed and a second forward fold of both the back 11 and front 10 is made on substantially dotted line 42. In this position 40 clasps 21 lie between the folds, and the tongues of the clasps project outwardly from the side edges of the bag. The tongues are then turned rearwardly onto the back and the folds are securely retained thereby. 45 Any suitable form of clasp will suffice for securing the folds of the flaps and top of the bag. All parts of the bag where the greatest strain occurs are reinforced, consequently the life of the bag is greatly prolonged.

Any suitable manner of closing the top and front of the bag will suffice, but I prefer to fold the contiguous portions of the front to close the same and to fold the upper 50 contiguous portions of the front and back to

close the top of the bag as heretofore described since the folds render the bag air tight, whereby the garments within the bag are fully protected from dust and insects and the like. Since the mouth of the bag not 60 only extends across the top of the bag but also part way down the front thereof, the bag may be opened to a much wider extent than bags heretofore in use for the purpose and thereby enable the user to insert a garment with great ease and with assurance that it is hanging in the bag without being wrinkled or crushed.

What I claim is:

1. A bag formed from a single sheet of 70 material having a permanently closed bottom and open top, the front of the bag being permanently closed in its lower portion, an opening in the upper portion of the front extending from the top edge thereof to the 75 said closed portion thereof, a flap on each side of the opening, an extension secured to one of the flaps along its longitudinal edge, the inner surface of which is adapted to be brought into contact with the inner surface 80 of the other flap, the said extension and said other flap when in juxtaposition being adapted to be folded together onto said flap to close said opening, and a reinforcement secured to the closed portion of the front adjacent the said opening, said reinforcement 85 being also secured to each flap.

2. A bag formed from a single sheet of 90 material having a permanently closed bottom and open top, the front of the bag being permanently closed in its lower portion, an opening in the upper portion of the front extending from the top edge thereof to the 95 said closed portion thereof, flaps on opposite sides of the opening which, collectively, are greater in width than the said closed portion of the front, a portion of the inner surface of each flap being adapted to be brought into contact with a portion of the inner surface of the other and when in juxtaposition, said 100 flaps being adapted to be folded together onto one of the same to close the opening, and means to secure the flaps in their folded position.

In witness whereof I hereunto subscribe 105 my name July, 1912.

CHARLES C. MILLER.
